UNITED STATES PATENT OFFICE.

ARTHUR TREVOR DAWSON AND GEORGE THOMAS BUCKHAM, OF WESTMINSTER, LONDON, ENGLAND, ASSIGNS TO VICKERS LIMITED, OF WESTMINSTER, ENGLAND.

ORDNANCE.

1,371,075.

Specification of Letters Patent. Patented Mar. 8, 1921.

Application filed November 18, 1917. Serial No. 201,845.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements in or Relating to Ordnance, of which the following is a specification.

This invention relates to ordnance or guns of the so-called non-recoil type in which the gun barrel is open at each end and receives in addition to the projectile and the powder charge a compensating mass which, when the gun is fired, is ejected from the rear end of the barrel, the inertia of this mass being substantially equal to that of the projectile so that the recoil force due to the firing of the projectile is more or less neutralized. In such guns it has been proposed to construct the gun barrel in two portions, viz., a fixed or forward portion and a movable or rear portion detachably connected to the former by interrupted threads or collars and to effect the displacement of the movable barrel-portion by an operating handle which, when moved, first angularly displaces the movable portion to disengage the interrupted threads or collars, then shifts it longitudinally and finally swings it across the breech face of the fixed barrel-portion about an axis parallel to the barrel, to enable the projectile, the powder charge and the compensating mass to be loaded into the fixed barrel portion; the complete operation of displacing the movable barrel-portion is thus performed by three separate motions of the operating handle.

According to the present invention we provide means whereby the aforesaid three movements of the movable barrel-portion can be effected by a continuous movement in one direction of the operating handle, the said means preferably comprising a rotary actuating sleeve, cylinder, or other member having rollers or projections which, during the continuous angular displacement of the sleeve in one direction, operate in the correct sequence to first unlock the movable barrel-portion, to then move it longitudinally and finally to swing it about the aforesaid horizontal axis.

In order that the said invention may be

clearly understood and readily carried into effect we will describe the same more fully with reference to the accompanying drawings, in which:

Figure 1 is a side elevation of a gun provided with a constructional form of our improvements.

Figs. 2 and 3 are respectively a rear elevation and a plan of Fig. 1.

Fig. 4 is a section taken approximately on the line 4—4 of Fig. 1 but with the movable or rear barrel-portion swung to its open or loading position.

Fig. 5 is a section taken approximately on the line 5, 5 of Fig. 1.

Fig. 6 is a local section on the line 6—6 of Fig. 1, but with the bracket D', herein-after referred to, omitted, and

Fig. 7 is a section taken approximately on the line 7, 7 of Fig. 1, and viewed from the rear; this view shows the parts in the position they occupy during the rearward movement of the rear barrel-portion, after the latter has been unlocked from the forward barrel-portion.

A is the fixed or forward barrel-portion and B is the rear barrel-portion which, as is well understood, is rotatably and slidably mounted in two guide bands b, b secured to a horizontal spindle B' rotatably mounted in brackets (one of which is shown at a in Fig. 1) on the forward barrel-portion A. The rear barrel-portion is detachably connected to the forward barrel-portion by interrupted threads or collars as aforesaid.

C is the aforesaid actuating sleeve which is rotatably mounted on the spindle B'. This sleeve in the example shown has bevel teeth at its forward end and also has two roller pins C' and C², the former being placed radially at the end removed from the bevel teeth and the other being arranged horizontally near the center. The bevel teeth engage with a bevel pinion D mounted in a bracket D' which is supported by the spindle B' and is fixed by being keyed to a projecting arm A' on the bracket a of the forward barrel-portion A. The radial roller pin C' is adapted to engage with a cam groove b' formed in a cam band B² fixed to the rear barrel-portion B.

The horizontally arranged roller pin C² is adapted to engage with a groove b² in the face of the said cam band. A hand lever E

is secured to the bevel pinion D which is held in the position corresponding to the locked position of the rear barrel-portion B, by a positive locking catch e engaging in a locking slot d' in a part D'^x of the bracket D'. This catch is moved to the released position by a sliding ferrule E' on the hand lever, this ferrule being used as a hand grip. The said hand lever preferably moves more than 360 degrees in effecting the complete displacement of the rear barrel-portion and in this event it is necessary for the locking catch e to be held out of its engaging position when re-passing the slot d' . For this purpose we provide a screw threaded collar E² which engages with screw threads on the part D'^x of the bracket D' and is keyed to the hand lever (for example by three keys e^2 on the collar E² engaging with corresponding slots in the boss of the hand lever) so that when the said collar is rotated by the hand lever it is displaced axially into a position to prevent the catch from reengaging with the locking slot until the rear barrel-portion B resumes its fully locked position. A spring controlled retaining catch b^x is mounted in the forward one of the guide bands b, b of the rear barrel-portion B and this catch is adapted to engage with a slot b'^x , formed in a key B^x on the rear barrel portion, while the latter is performing its swinging movement, thereby locking it in its withdrawn position. The said retaining catch comes against the head of a steel screw d'^x (Fig. 4) attached to the bracket D' when the rear barrel-portion is being swung into alignment with the forward barrel-portion after loading and the said catch is thereby disengaged from its slot b'^x .

When the gun is to be loaded the aforesaid sliding ferrule E' is moved along the handle of the hand lever E to disengage the locking catch e and the hand lever is then rotated. The consequent movement of the actuating sleeve C causes the horizontally arranged roller pin C² on this sleeve to angularly displace the rear barrel-portion by the engagement of the said roller-pin with the groove b^2 in the face of the cam band B² fixed to this barrel-portion, thereby unlocking the latter from the forward barrel-portion. On the completion of this unlocking movement the radial roller pin C' on the actuating sleeve engages with the cam groove b' in the said band and thereby moves the rear barrel-portion B rearward so that its front face comes clear of the breech face of the forward barrel-portion. During this rearward movement the aforesaid key B^x on the rear barrel-portion enters a key-way on the forward one of the guide bands b, b and the said barrel-portion is thereby prevented from moving about its axis when in the withdrawn position. The rearward movement of the rear barrel-portion is arrested by a stop b^3 thereon coming against the said guide band, and the radial roller pin C' is then unable to move farther along its groove b' in the cam band, whereby the sleeve C becomes for the time being rigidly connected to the rear barrel-portion. Consequently, as a groove B³ on the cam band B² of the rear-barrel-portion has at this time become clear of a guide or projection D³ (see Fig. 7) which is formed on the bracket D' and which during the rearward movement of the rear barrel-portion had prevented the latter from swinging about the axis of the spindle, further displacement of the actuating sleeve C will cause the rear barrel-portion together with its guide bands to be swung to its open position about the spindle B', for enabling the cartridge comprising the projectile, the powder charge and the compensating mass to be loaded into the rear end of the forward barrel-portion. The rear barrel-portion at this time rests upon an arm D^{xx} which is integral with the bracket D'. During the said swinging movement the catch b^x engages with the slot b'^x to lock the rear barrel-portion in the withdrawn position and the said barrel-portion operates a suitable extractor F (Fig. 4) for ejecting or unseating the cartridge case. When the hand lever is rotated in the reverse direction after the gun has been loaded, the rear barrel-portion is first swung into line with the forward barrel-portion, is then moved in a forward direction and is finally angularly displaced about its axis to lock it to the forward barrel-portion.

The rotary actuating sleeve C is formed with a cam-groove C^x serving to retract the striker of the firing mechanism before any unlocking movement is imparted to the rear barrel-portion and to afterward effect the cocking of the striker. This arrangement is fully set forth in the specification of our patent application Serial No. 201,846, filed November 13th, 1917.

What we claim and desire to secure by Letters Patent of the United States is:

1. In non-recoil ordnance, the combination with the fixed barrel-portion and the movable barrel-portion, of an operating device and means whereby a continuous movement in one direction of said device unlocks the movable barrel-portion from the fixed barrel-portion, said movement taking place in a single plane relative to said fixed portion, then displaces the movable barrel-portion longitudinally and finally moves it about a longitudinal axis across the breech face of the fixed barrel-portion to enable the latter to be loaded.
2. In non-recoil ordnance, the combination with the fixed barrel-portion and the movable barrel-portion, of an operating handle and means whereby a continuous movement in one direction of said handle

unlocks the movable barrel-portion from the fixed barrel-portion, said movement taking place in a single plane relative to said fixed portion, then displaces the movable barrel-portion longitudinally and finally moves it about a longitudinal axis across the breech face of the fixed barrel-portion to enable the latter to be loaded.

3. In non-recoil ordnance, the combination with the fixed barrel-portion and the movable barrel-portion of an operating handle, a rotary member actuated by said handle and projections on said member which, during the continuous angular displacement of said member in one direction, operate in the correct sequence to first unlock the movable barrel-portion, to then move it longitudinally and finally to swing it about a horizontal and longitudinal axis.

20 4. In non-recoil ordnance, the combination with the fixed barrel-portion and the movable barrel-portion, of an operating handle, a rotary sleeve actuated by said handle and projections on said sleeve which, during the continuous angular displacement of said sleeve in one direction operate in the correct sequence to first unlock the movable barrel-portion, to then move it longitudinally and finally to swing it about a horizontal and longitudinal axis.

25 5. In non-recoil ordnance, the combination with the fixed barrel-portion and the movable barrel-portion, of an operating handle, means whereby a continuous movement, in one direction of said handle unlocks the movable barrel-portion from the fixed barrel-portion, then displaces the movable barrel-portion longitudinally and finally

moves it about a longitudinal axis across the breech face of the fixed barrel-portion to 40 enable the latter to be loaded, a locking catch for said handle and means for holding said catch in the disengaging position during the rotation of the handle.

6. In non-recoil ordnance, the combination with the fixed barrel-portion and the movable barrel-portion, of an operating device, means whereby a continuous movement in one direction of said device unlocks the movable barrel-portion from the fixed barrel-portion, then displaces the movable barrel-portion longitudinally and finally moves it about a longitudinal axis across the breech face of the fixed barrel-portion to enable the latter to be loaded, and means for preventing the movable barrel-portion from being displaced about its axis after it has been withdrawn from the fixed barrel-portion.

7. In non-recoil ordnance, the combination with the fixed barrel-portion and the movable barrel-portion of an operating device, means whereby a continuous movement in one direction of said device unlocks the movable barrel-portion from the fixed barrel-portion, then displaces the movable barrel-portion longitudinally and finally moves it about a longitudinal axis across the breech face of the fixed barrel-portion to enable the latter to be loaded, and a retaining catch for locking the movable barrel-portion in 65 its withdrawn position during its movement across the face of the fixed barrel-portion.

In testimony whereof, we affix our signatures.

ARTHUR TREVOR DAWSON.
GEORGE THOMAS BUCKHAM.
